Inventor:

UNITED STATES PATENT OFFICE.

PETER SZEREMETA, OF HAMMOND, INDIANA.

RAIL-JOINT.

1,220,023.

Specification of Letters Patent. Patented Mar. 20, 1917.

Application filed September 8, 1916. Serial No. 119,081.

To all whom it may concern:

Be it known that I, PETER SZEREMETA, a subject of the Emperor of Russia, residing at Hammond, in the county of Lake 5 and State of Indiana, have invented certain new and useful Improvements in Rail-Joints; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

My invention relates to railroad rail joints, and has for its object to provide a rail joint in which the abutting ends of the rails will be locked together by means 20 of a chair conforming to the shape of the base and web and under face of the tread of the rail, and a locking device of special construction which dispenses with bolts and nuts and affords a lock permanent in character. 25 The joint furthermore embodies features of construction which adapt it when used in connection with a movable frog or switch rail to permit deflection or side movement of the switch rail and possess the 30 same advantages of construction as when applied at the abutting ends of stationary rails.

To the accomplishment of the foregoing and such other objects as may hereinafter 35 appear the invention consists in the features hereinafter particularly described and then sought to be clearly defined by the claims, reference being had to the accompanying drawings forming a part hereof, and in 40 which—

Figure 1 is a plan view embodying the invention;

Fig. 2 a horizontal section on line 2—2 of Fig. 3;

Fig. 3 is a side elevation;

Fig. 4 is a cross section on line 4—4 of Fig. 3;

Fig. 5 is a side elevation showing chair with movable wing;

Fig. 6 a horizontal section on line 6—6 of Fig. 5, and showing in dotted lines shifted position of movable rail;

Fig. 7 is a cross section on line 7—7 of Fig. 5;

Fig. 8 is a fragmentary plan view of the chair, with movable wing removed;

Fig. 9 is a perspective of the movable wing of the chair.

In the drawing the numeral 1 designates stationary or fixed rails and 2 a movable frog or switch rail, and 3 designates the rail-joint chair. This chair has a base 4 corresponding to the base-flange of the rail, and side cheeks 5 corresponding to the web of the rail and which at their upper ends 65 bear against the under face of the tread of the rail so that the base flange of the rail rests upon the base of the chair and its tread rests upon the upper edges of the cheeks of the chair whereby are formed two 70 bearing supports for the rail while the sides of the web of the rail are braced or have bearing against the cheeks of the chair, so that the abutting ends of the meeting rails are prevented from dropping one below the 75 other. The chair and the rails are locked together at the joint by a key 6 consisting of a bar 7 having laterally projecting pins 8 which are passed through registering openings 9 formed in the cheeks of the chair 80 and in the webs of the rail at opposite sides of the joint between the abutting ends of the rails, the opposite ends of the bar 7 being bent or curved as indicated at 10 so as to engage or hug the opposite ends of 85 the chair and thus relieve the pins of strains longitudinally of the rails, and the chair cheek next to the bar 7 is formed with a groove 11 for the bar to lie in so as to relieve the pins of vertical strains. A locking pin 12, preferably of spring steel, is passed through holes made in the lateral pins so as to hold them in place. The locking key described dispenses with bolts and nuts and securely locks the parts together 95 without liability of the parts becoming loose and a necessity of tightening the parts to take up slack and looseness.

The chairs 3 may be rigid throughout when to be applied to fixed or stationary 100 rails, or may have a flexible or yielding wing constituting a part or section of one cheek of the chair when to be applied to a movable frog or switch rail, and while this form may also be used with the stationary 105 rails yet for such use the yielding wing or section may be omitted, and the chair made rigid throughout. The yielding section or wing is designated by the numeral 14 and has a vertical wall 15 forming a part of one 110 cheek of the chair, and a horizontal portion 16 forming a part of the base of the chair

and a depending tongue 17 which is preferably dovetail in shape and adapted to fit a dovetail groove or cavity 18 formed in the chair. The base of the chair is formed 5 with a cavity 19 in which is fitted a spiral spring 20 that is formed with an extension 21 adapted to fit in a socket 22 to prevent movement of the spring. One end 23 of the spring is fitted in a hole or bore 24 formed in the base of the chair to aid in holding the spring in place and its other end is formed into a loop 25 to receive the tongue 17 of the wing so that when the wing is spread outward the spring will dis- 10 tend or stretch and when the pressure is relieved the spring will tend to restore the wing to its normal or original position. The wing section is secured to the cheek of the chair by means of a key 26 fitted in a dove- 15 tailed groove 27 formed in the face of the cheek and vertical wall of the wing, said key preferably being made of stiff spring metal and formed with openings or holes 28 which will register with corresponding 20 holes made in the cheeks of the chair and web of the rails to receive the laterally ex- 25 tends pins 29 and 30 of the bar 31 constituting the key for locking the chair and rails together. This key is substantially the same as the key previously described 30 except that only two of its pins are formed with holes to receive the lock pin, the other pins 30 of the bar being adapted to pass through openings in the lock pin and pref- 35 erably being slightly deflected from a horizontal, or downwardly as shown, so as to prevent the lock pin from disengaging from the pins. The lock-pin is made of stiff spring metal and has a reduced portion 40 31 to pass through the holes in the pins 29 and a flattened portion 32 formed with holes 33 to receive the pins 30. The lock pin is thus held against longitudinal movement, and also against disengagement from the 45 pins 30 as the latter are slightly bent at their ends so that when the flattened portion of the lock pin is sprung into engagement with the pins, the lock-pin is held in place and all the parts securely locked together 50 without the use of bolts and nuts. By se- 55 curing the movable frog or switch rail and the chair together as described a slight lat- eral yielding of the switch rail under spring tension is permitted when necessary and when pressure on the rail is relieved the 60 spring lock-pin and the coiled spring will restore the wing to its normal position. The same features of construction and advan- 65 tages described for the chair applied to the 60 stationary rails are found in the chair for the movable frog or rail, the latter being additionally provided with the yielding wing for the purposes specified. As before mentioned the chair with the yielding wing 65 could be applied at all joints but for the sta-

tionary rail joints the yielding wing may be omitted and the chair made rigid through- out.

I have illustrated and described with par- 70 ticularity the preferred details of the sev- 75 eral parts but changes can be made therein and essential features of the invention re- tained.

Having described my invention and set 75 forth its merits what I claim is:

1. A rail-joint comprising a chair formed with a base and side cheeks to receive the bottom flanges and webs of the adjacent ends of rails, with the upper ends of the cheeks bearing against the under face of 80 the tread of the rails, a locking key consisting of a bar to bear against one cheek of the chair and provided with laterally ex- 85 tends pins to pass through the cheeks of the chair and webs of the rails, and a lock- pin engaging the ends of the pins to prevent withdrawal of the pins.

2. A rail-joint comprising a chair formed with a base and side cheeks to receive the bottom flanges and webs of the adjacent ends 90 of the rails, a locking key consisting of a bar to bear against one cheek of the chair and formed with deflected ends to embrace opposite ends of the chair and having later- 95 ally extending pins to pass through the cheeks of the chair and webs of the rails, and a lock-pin engaging the ends of the pins to prevent withdrawal of the pins.

3. A rail-joint comprising a chair formed with a base and side cheeks to receive the bottom flanges and webs of the adjacent ends of rails, a locking key consisting of a bar to bear against one cheek of the chair and provided with laterally extending pins 100 to pass through the cheeks of the chair and webs of the rails, one cheek of the chair being formed with a groove to receive the bar of the key, and a lock-pin engaging the ends of the pins to prevent withdrawal 105 of the pins.

4. A rail-joint comprising a chair formed with a base and side cheeks to receive the bottom flanges and webs of the adjacent ends of rails, one cheek of the chair having a movable wing to permit lateral movement 115 of one rail, a locking key consisting of a bar to bear against one cheek of the chair and provided with pins extending through the cheeks and wing of the chair and webs of the rails, and a lock-pin engaging the ends of the pins to prevent withdrawal of the locking key.

5. A rail-joint comprising a chair formed with a base and side cheeks to receive the bottom flanges and webs of the adjacent 120 ends of rails, one cheek of the chair having a resilient wing to permit lateral movement of one rail, a locking key consisting of a bar to bear against one cheek of the chair and provided with pins extending through the 125 130

cheeks and wing of the chair and webs of the rails, and a spring lock-pin having one end passing through some of the pins of the locking-key and a flattened portion receiving other pins of the locking-key.

6. A rail-joint comprising a chair formed with a base and side cheeks to receive the bottom flanges and webs of the adjacent ends of rails, the base of the chair being formed with a cavity to receive a spring and at the side with a dovetail socket, a spring fitting in the cavity of the chair-base and formed with extensions to secure it in the cavity and with a loop, a movable wing forming a part of one cheek of the chair and a part of the base of the chair

and having a tongue to fit in the loop of the spring and the socket of the chair, a locking key consisting of a bar to bear against one cheek of the chair and provided with pins extending through the cheeks and wing of the chair and webs of the rails, and a lock-pin having one end passing through some of the pins of the locking-key and a flattened portion receiving other pins of the locking key.

In testimony whereof I affix my signature in presence of two witnesses.

PETER SZEREMETA.
